US00D993725S

(12) **United States Design Patent** (10) Patent No.: **US D993,725 S**
(45) Date of Patent: **** Aug. 1, 2023**

(54) **SLOPED CHANNEL CUTTING BOARD**

(71) Applicant: **Pit Barrel Cooker Co, LLC,**
Louisville, KY (US)

(72) Inventor: **Noah E Glanville**, Murphy's, CA (US)

(**) Term: **15 Years**

(21) Appl. No.: **29/794,126**

(22) Filed: **Jun. 10, 2021**

(51) LOC (14) Cl. **07-04**

(52) U.S. Cl.

USPC **D7/698**

(57) **CLAIM**

The ornamental design for a sloped channel cutting board, as
shown and described.

DESCRIPTION

FIG. 1 is a perspective view of a sloped channel cutting board;

FIG. 2 is a side view of FIG. 1;

FIG. 3 is a top plan view of FIG. 1;

FIG. 4 is an opposite side view of FIG. 2;

FIG. 5 is a bottom plan view of FIG. 3;

FIG. 6 is an end view of FIG. 1;

FIG. 7 is an opposite end view of FIG. 6;

FIG. 8 is a top plan view of FIG. 1;

FIG. 9 is a cross-section about lines 9-9 of FIG. 8;

FIG. 10 is a top plan view of FIG. 1;

FIG. 11 is a cross-section about lines 11-11 of FIG. 10; and,

FIG. 12 is a bottom perspective view of FIG. 1.
